GATE VALVE CONTROL

James Trefil, Berwyn, Ill., and Nicholas P. Arvan, Milwaukee, Wis., assignors to Crane Co., Chicago, Ill., a corporation of Illinois

Filed Mar. 2, 1967, Ser. No. 6,039

Term of patent 14 years

(Cl. D78—1)

The single figure is a perspective view of a gate valve control showing our new design.

The rear and side not shown are mirror images of the front and side shown. The valve body and handwheel shown in broken lines are included for illustrative purposes only.

We claim:

The ornamental design for a gate valve control, as shown and described.
